UNITED STATES PATENT OFFICE.

LLOYD V. LEWIS, OF EDGEWOOD BOUCHE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

Original application filed March 4, 1918, Serial No. 220,172. Divided and this application filed December 6, 1921. Serial No. 520,322.

To all whom it may concern:

Be it known that I, LLOYD V. LEWIS, a citizen of the United States, residing at Edgewood borough, in the county of Allegheny and State of Pennsylvania, have invented certain new and useful Improvements in Railway-Traffic-Controlling Systems, of which the following is a specification.

My invention relates to railway traffic controlling systems, and particularly to systems of the type wherein traffic governing means located on a train or vehicle is controlled by energy received from the trackway.

The present application is a division of my copending application filed on the 4th day of March, 1918, Serial No. 220,172, for railway traffic controlling systems.

I will describe certain forms of traffic controlling systems embodying my invention, and will then point out the novel features thereof in claims.

In the accompanying drawings, Fig. 1 is a diagrammatic view showing one form of traffic controlling system embodying my invention. Figs. 2 and 3 are views showing modifications of the system shown in Fig. 1 and also embodying my invention.

Similar reference characters refer to similar parts in each of the views.

Referring first to Fig. 1, the reference characters R, R' designate the track rails of a railway, which rails are divided by insulated joints 2 to form blocks A—B, B—C, etc. Traffic along the railway is normally in the direction indicated by the arrow. Extending along the trackway is an auxiliary conductor X which is preferably, though not necessarily, located midway between the track rails as shown in the drawing. This auxiliary conductor is divided, by insulation 2^a or otherwise, at points substantially opposite the insulations in the track rails, and is further divided in a similar manner at a point E within each block to form a rear and a forward section for the block. Thus within the limits of block A—B this auxiliary conductor is divided into a rear section A—E and a forward section E—B.

Each block is provided with a track circuit comprising as usual the track rails of the block, a source of alternating signaling current connected across the rails adjacent

the exit end of the block, and a track relay connected across the rails adjacent the entrance end of the block. The source of current for each track circuit is a secondary 3 of a transformer which is designated T with an exponent corresponding to the location, and the relay for each track circuit is designated by the reference character H, with an exponent corresponding to the location. For example, the track circuit for block B—C comprises the secondary 3 of transformer T^c and relay H^c. Each secondary 3 is connected with the track rails by conductors 4 and 5, which conductors include respectively the two windings 6 and 6^a of a reactor W, the function of which will be explained hereinafter. The track relay H for each block is connected directly across the track rails of the block, as shown.

The primary windings of the several transformers T are connected with transmission mains P which extend along the railway and to which alternating signaling current is supplied by suitable means, such as by a generator N.

Means are provided for each block for supplying alternating signaling current to the corresponding forward section of the auxiliary conductor X, this supply being controlled by the track relay for the block next in advance so that such supply is discontinued when the block in advance is occupied. As here shown, this current is supplied by a secondary 7 of the transformer T at the exit end of the block, and is controlled by a contact 9 of the track relay for the block next in advance. The return circuit for the current in conductor X is completed through the track rails in such manner that said current does not interfere with the supply of track circuit current to the track rails from transformer secondary 3. For example, the circuit for the advance section E—B of the auxiliary conductor for block A—B is from the secondary 7 of transformer T^b, through wire 8, contact 9 of track relay H^b, wire 10, resistance 11, wire 10^a, conductor X, to wire 12; the circuit then divided into two similar branches, one branch being through winding 13 of a reactor M, wire 14, rail R', wire 4 at location B, winding 6 of a reactor W, left-hand half of transformer secondary 3, and wire

15 to secondary 7. The other branch is from wire 12, through winding 13^a of reactor M, wire 14^a, rail R, wire 5, winding 6^a, of reactor W, right-hand half of secondary 3, and wire 15 to secondary 7. The reactor M comprises the two windings 13 and 13^a on an iron core 16, these windings being so arranged that when equal currents flow therethrough in the manner just traced, 10 that is, from conductor X to the track rails or vice-versa, the magnetic fluxes produced by the currents in the two windings oppose each other and so are neutralized, whereby this device offers a low impedance to such 15 current flow. The device offers high impedance, however, to the flow of track circuit current from rail to rail, because such flow is through the two windings 13 and 13^a in series. The reactor W comprises the two 20 windings 6 and 6^a on an iron core 17, these windings being so arranged that when currents flow therethrough from rails R and R' to secondary 7 as described, the fluxes produced by the two windings neutralize 25 each other and so the device offers a low impedance to such current flow. The track circuit current, however, flows from secondary 3 through winding 6 to rail R' and back through winding 6^a (or vice-versa), hence 30 as to this current the windings 6 and 6^a are in series and so the device W offers considerable impedance to such current flow. One function of this device is to prevent an abnormal flow of current from secondary 35 3 when the track rails are bridged by the wheels and axles of a car or train. Another function will appear hereinafter.

The branch circuits from conductor X to secondary 7 just traced pass in opposite directions through the two halves of secondary 3, consequently secondary 3 will produce no electromotive force in the circuit of secondary 7. Likewise, since the circuit of secondary 7 is connected to the circuit of secondary 3 at two points both having an instantaneous potential midway between the potentials at the terminals of secondary 3, and hence having the same potential, it follows that secondary 7 will produce no electromotive force in the circuit of secondary 3.

Inasmuch as the supply of current to section E-B of the auxiliary conductor X is controlled by front contact 9 of the track relay for block B-C, it is apparent that 55 this conductor section will be supplied with current only when block B-C is unoccupied.

Means are also provided for each block for supplying signaling current to the rear 60 section of auxiliary conductor X for the block, this current supply likewise being controlled by the track relay for the block next in advance. The control in this instance is such, however, that current is con-

stantly supplied to the rear conductor section, but that this current is of one relative polarity or the reverse according as the block next in advance is clear or occupied. For example, when block B-C is clear, so that relay H^B is closed, the circuit for the rear conductor section A-E of block A-B is from the left-hand section of winding 18 of transformer T^B, through wire 19, front point of contact 20 of relay H^B, wire 21, resistance 22, wire 21^a, section A-E of conductor X, wire 12, thence in opposite directions through the two similar windings 13 and 13^a of reactor M at location A, the two rails R and R' in multiple, thence in opposite directions through the two windings of reactor W at location B and of secondary 3 of transformer T^B, wire 15 to the middle point of secondary 18. The action of reactors M and W and of secondary 3 on current flowing in this circuit is the same as the action of these devices on the current flowing through the forward section of conductor X. The current which is thus supplied to the rear conductor section I will term current of "normal" polarity. When track relay H^B is open, due to the presence of a car or train in block B-C or to some abnormal condition, the current for conductor section A-E flows from the right-hand half of secondary 18 of transformer T^B, through wire 22^a, back point of relay contact 20, thence as before to the middle point of secondary 18. This current I will term current of "reverse" polarity.

It will be clear, therefore, that the current in conductor section A-E will be of normal or reverse polarity according as track relay H^B is energized or de-energized, that is, according as block B-C is clear or is occupied. Furthermore, the currents in the sections of conductor X due to secondaries 7 and 18 are displaced in phase from the currents in the track circuits due to secondaries 3, because the circuits for the conductor sections include resistances 11 and 22, whereas the track circuits include the reactor W.

As shown in the drawing, block A-B is occupied by a car or other railway vehicle, represented by an axle and pair of wheels V. Mounted on this vehicle in advance of the forward axle are three U-shaped laminated iron cores 23, 24, and 25, each core being transversely disposed with respect to the track rails with its legs pointing downwardly. The cores 23 and 24 are located directly above the track rails R and R', respectively, whereas core 25 is located directly above the auxiliary conductor X. It is apparent, therefore, that when alternating current flows in track rail R, some of the magnetic lines of force surrounding this rail will pass through core 23 and so there will be an alternating magnetic flux in this core. Cur-

rents in rail R' and in conductor X similarly create magnetic flux in cores 24 and 25, respectively.

Cores 23 and 24 are provided with coils 26 and 26^a, respectively, and core 25 is provided with a coil 27. Alternating flux in any one of the cores will, of course, create an alternating difference of potential across the terminals of the coil on such core. Coils 26 and 26^a are included in series in a circuit which comprises coil 26, wire 28, coil 26^a, wire 29, condenser 30, and wires 31, 32 and 33, which circuit I will, for convenience, designate circuit a . Coils 26 and 26^a are connected in this circuit in such manner that the potentials created by currents flowing in the same direction in the track rails, such as the current due to secondary 7, neutralize each other and so cause no current in circuit a , but that the potentials created by currents flowing in opposite directions in the track rails, such as the current due to secondary 3, are additive, and so cause a flow of alternating current in circuit a . That component 25 of the track current which flows in opposite directions in the two rails, therefore, induces alternating current in circuit a , but the currents supplied to the auxiliary conductor do not create current in circuit a because they 30 comprise a component of the track current which flows in the same direction in the two rails.

Coil 27 is included in a circuit b , which circuit comprises the coil 27, wire 34, condenser 35, and wires 32 and 36.

Coils 26 and 26^a are so wound as to have high inductance, and condenser 30 has comparatively small capacity, and the circuit including these elements (circuit a) is tuned 40 to resonance at the frequency of the signaling current, hence condenser 30 will be charged to a comparatively high potential by the comparatively feeble current induced in circuit a by current in the track rails. Circuit b is also tuned to resonance at the signaling current frequency, with similar results. It follows that when the vehicle V occupies a block in which signaling currents are supplied to the track circuit and to the auxiliary conductor X , currents will flow in circuits a and b on the vehicle, and these currents will be of the same frequency as, and will have the same phase displacement, as the currents in the track circuit and auxiliary conductor respectively. These currents, and the consequent potentials impressed on condensers 30 and 35, are, however, too feeble to reliably actuate traffic governing apparatus of a rugged character, 50 hence I preferably provide suitable amplifying or relaying apparatus, which, in the form here shown, comprises electron relays or amplifiers K' , K^2 , K^3 and K^4 . Each of these relays comprises a vacuum bulb 41 containing a filament 38, a plate 40, and a grid

39 interposed between the two. The filaments 38 of these relays are constantly heated by a battery 43 through circuits which will be obvious from the drawing.

Condenser 30 of circuit a is connected 70 across the filament 38 and grid 39 of relay K' , a blocking condenser 37 being included in the circuit. The plate circuit of relay K' is from a battery 44, through wires 45 and 46, across the gap between filament 38 and plate 40 of relay K' , primary of transformer 49, wire 48 to battery 44. A condenser 47 is connected across the terminals of the primary of transformer 49, the circuit including this condenser and the transformer primary being tuned to resonance at the frequency of the signaling current. The secondary of transformer 49 is connected across the filament 38 and grid 39 of the electron relay K^2 . The plate circuit of this latter relay is from battery 44 through wires 45, 31, 50 and 51, the gap between filament 38 and plate 40 of relay K^2 , wire 52, winding 55 of a relay F , and wire 54 to battery 44. Connected across winding 55 is a condenser 53, 90 the circuit comprising condenser 53 and winding 55 being tuned to resonance at the frequency of the signaling current. It will be seen, therefore, that relay winding 55 will be supplied with current of the same frequency as that which is supplied to the track circuit, but that this current will be of considerably greater magnitude and so is of sufficient value to reliably actuate an electromagnetic or induction motor relay of rugged 100 design.

The current induced in the vehicle-carried circuit b is similarly amplified by the two electron relays K^3 and K^4 , the plate circuit of the latter relay being from battery 44, 105 through wires 45, 31, 50 and 56, the gap between the filament and the plate of relay K^4 , wire 57, winding 59 of relay F , thence through the wire 54 to battery 44. Connected across winding 59 is a condenser 58. 110 Winding 59 is, therefore, supplied with current of the same frequency and relative phase as the current supplied to the section of the auxiliary conductor X over which the vehicle happens to be, but the current in winding 59 is, of course, of considerably 115 greater magnitude than that which flows in circuit b .

The relay F is of the induction motor type, comprising a rotor member 60 which responds to currents displaced in phase in the windings 55 and 59, and which, in turn, actuates a contact member 61. Inasmuch as the currents in the track circuits and in the auxiliary conductor X are displaced in 120 phase, it follows that the currents in relay windings 55 and 59 will similarly be displaced in phase, so that torque will be exerted on the rotor member 60 in one direction or the other, depending on the relative 125 130

instantaneous polarities of the currents induced in circuits *a* and *b*. In other words, contact member 61 will be swung in one direction or the other from its middle position 5 to which it is biased, according as the current in circuit *b* has one instantaneous polarity or the other with relation to the current *a*, that is, according as the current in conductor section A—E is of normal or reverse polarity.

The relay F may be employed to control any kind of traffic governing apparatus that may be desired. As here shown, this relay controls a signal S comprising three incandescent lamps G, Y and R, which lamps when illuminated indicate "proceed", "caution" and "stop", respectively. These lamps are supplied with current from a battery 98. When either or both windings of relay F are de-energized, so that contact member 61 occupies its intermediate position, contact 61-62 closes the circuit for the lamp R, which circuit will be obvious from the drawing. When both windings of relay F are energized and the current in winding 59 is of normal polarity, contact member 61 is swung to the left into engagement with contact 64^a, so that the proceed lamp G is illuminated. When both relay windings are energized and the current in winding 59 is of reverse polarity, contact 61-64 is closed, so that the caution lamp Y becomes illuminated. It will be seen, therefore, that signal S on the vehicle indicates "stop", "caution" or "proceed", according as relay F is de-energized, energized in reverse direction, or energized in normal direction.

The operation of the system shown in Fig. 1 is as follows:

40 The block next in advance of location C is occupied by a vehicle which is represented by a pair of wheels and an axle V', so that relay H^c is de-energized. Current of reverse polarity is, consequently, supplied to the rear section B—E of the auxiliary conductor for block B—C, whereas the forward conductor section E—C for this same block is de-energized. Track relay H^b is energized, so that forward conductor section E—B of block A—B is energized and current of normal polarity supplied to the rear conductor section A—E of this block. Vehicle V being over the rear conductor section of block A—B, circuit *a* is supplied 45 with current from the track circuit and circuit *b* receives current of normal polarity due to the current in the conductor X. Relay F is, consequently, energized in normal direction, so that signal S indicates "proceed". As the vehicle V passes into the forward section of block A—B, no change occurs, because, of course, the current supplied to the forward conductor section is of normal polarity. When the vehicle V passes 50 into block B—C, the circuit *a* continues to

be energized due to track circuit current, but current of reverse polarity is now supplied to circuit *b*. Relay F, therefore, becomes energized in reverse direction, so that lamp Y becomes illuminated and signal S indicates "caution". After the vehicle passes point E in block B—C, the circuit *b* becomes de-energized, so that relay F likewise becomes de-energized, whereby lamp R becomes illuminated so that signal S then indicates "stop".

Assuming that vehicle V' remains in the position shown and that the block in advance of the one occupied by this vehicle is unoccupied, it follows that the rear conductor section of the block occupied by vehicle V' is supplied with current of normal polarity. Those portions of the track rails of this block which are in the rear of vehicle V' are not supplied, however, with track circuit current because this current is shunted by the wheels and axles of vehicle V'. If, therefore, vehicle V enters the block occupied by vehicle V', winding 59 of relay F will become energized, but winding 55 will become de-energized, so that relay F will continue to be de-energized and so signal S will continue to indicate "stop".

In the system shown in Fig. 1, the relative polarity of the current in the track circuits is always the same, that is, the track circuits are of the type which is generally known as "non-polarized". This system, then, is readily adapted for application to a railway which is already equipped with a signaling system embodying alternating current track circuits of the non-polarized type. When it is desired to apply a system embodying my invention to a railway which is already provided with a signaling system comprising "polarized" alternating current track circuits, the system shown in Fig. 2 may be preferable. This system does not interfere with the existing roadside signals, or with the control of these signals by the existing three-position alternating current track relays. The substantial difference between the systems shown in Figs. 1 and 2, so far as the present invention is concerned, is that in Fig. 1 the relative polarity of the track circuit current is constant and that of the current in the rear sections of the auxiliary conductor X is reversible, whereas in the system shown in Fig. 2 the polarity of the track circuit current is reversible and that of the currents in the auxiliary conductor X is constant.

Referring now to Fig. 2, the arrangement of blocks and of auxiliary conductor sections is the same as that shown in Fig. 1. In Fig. 2, however, each track relay, which is here designated by the reference character J with an exponent corresponding to the location, is of the three-position type,

comprising two windings 65 and 66, the former of which is connected directly with the track rails and the latter of which is constantly supplied with alternating current from the left-hand section of secondary 67 of the adjacent transformer T. Each of these relays, therefore, responds to reversals of the relative polarity of the current in the corresponding track circuit with respect to that of the transmission line P; in other words, the contact fingers 68, 69 and 70 of each relay are swung to the left when the polarity of the track circuit is normal, and to the right when the polarity of the track circuit is reverse, and these contact fingers occupy vertical or intermediate positions when the track winding of the relay is de-energized.

Located at the entrance of each block is a roadside signal which is designated by the reference character S with an exponent corresponding to the location of the signal. As here shown, these signals are of the types known as "light signals", each comprising three electric lamps, G', Y' and R', indicating "proceed", "caution" and "stop", respectively, when illuminated. Each signal S is controlled by contact finger 68 of the adjacent track relay in such manner that lamp G' is illuminated when the relay is energized in the normal direction, lamp Y' is illuminated when the relay is energized in reverse direction, and lamp R' is illuminated when the relay is de-energized. These lamps are supplied with current from the left-hand section of secondary 67 of the adjacent transformer, and the circuits will be obvious from the drawing without further explanation.

The supply of current to the track circuit of each block is controlled by contact 69 of the track relay for the block next in advance, in such manner that the polarity of the track circuit current is normal when the relay is energized in either direction, and reverse when the relay is de-energized. The immediate source of supply for each track circuit is a transformer designated by the reference character 71 with an exponent corresponding to the location, the secondary of which transformer is connected across the track rails through a reactor W. The circuit for the primary of the transformer 71^c, when relay J^c is de-energized, is from the middle terminal of secondary 67 of transformer T^c, through wire 72, primary of transformer 71^c, wire 73, contact finger 69 of relay J^c, and wire 74 to the right-hand terminal of transformer secondary 67. The current which is thus supplied to the track circuit of block B-C is of reverse polarity. When relay J^c is energized in either normal or reverse direction, the circuit for the primary of transformer 71^c is from the middle terminal of secondary 67 of transformer T^c, through wire 72, primary of transformer 71^c, wire 73, contact finger 69, contact 81 or 82, wire 83 and wire 76 to the left-hand terminal of transformer secondary 67. The current which is then supplied to the track circuit of block B-C is of normal polarity.

The current for the advance section of conductor X in each block is supplied from the right-hand section of secondary 67 of the transformer T at the exit end of such block through a transformer which is designated by the reference character 78 with an exponent corresponding to the location, and this supply is controlled by contact 70 of the track relay for the block next in advance. The primary circuit for transformer 78^c, for example, is from the middle point of secondary 67 of primary T^c, through wire 72, primary of transformer 78^c, wire 77, contact finger 70, and wire 76 to the left-hand terminal of secondary 67. It will be seen that this circuit will be closed when track relay J^c is energized in either direction, but opened when this track relay is de-energized. The secondary circuit for transformer 78^c is from the secondary of this transformer through wire 79, resistance 89, conductor section E-C, reactor M at the rear end of such conductor section, rails R and R' in multiple, wires 84 and 85 in multiple, the windings of reactor W in multiple, the two halves of the secondary of transformer 71^c in multiple, and wire 80 to the secondary of transformer 78^c.

The rear section of conductor X for each block is supplied with current from a secondary 75 of the transformer T at the entrance end of such block. For example, the circuit for section B-E of this conductor in block B-C is from secondary 75 of transformer T^b, through wire 86, resistance 87, conductor section B-E in block B-C, reactor M at the forward end of such conductor section, rails R and R' in multiple, reactor M at the rear end of said conductor section, and wire 88 to secondary 75. It will be seen, therefore, that current is constantly supplied to this section of the auxiliary conductor X.

Owing to the fact that the track circuit current must pass through reactors W in such direction that these devices are reactive to such current, and to the fact that the currents for the sections of conductor X must pass through resistance 87 or 89, it follows that the track circuit current and the currents in the auxiliary conductors are displaced in phase.

The apparatus on the vehicle V in Fig. 2, is similar to that shown in Fig. 1, except that in Fig. 2 I have shown only one electron relay for each winding of the vehicle governing relay F. Condenser 30 in circuit a is connected with the filament and grid of relay K', whereas condenser 35 of circuit b

is connected with the filament and grid of relay K^a . Relay winding 55 is connected in the plate circuit of electron relay K' , and relay winding 59 is connected in the plate circuit of electron relay K^b . I have shown only two electron relays in Fig. 2 to indicate that this arrangement may be used instead of that shown in Fig. 1, if considered desirable. It is understood, however, that the single pair of electron relays may be used in combination with the trackway circuits shown in Fig. 1, and that likewise two pairs of such relays may be used in combination with the trackway circuits shown in Fig. 2.

18 The operation of the system shown in Fig. 2 will now be readily understood and may be briefly explained as follows:

Inasmuch as the block directly in advance of location C is occupied by vehicle V, track relay J^c is de-energized, so that signal S^c indicates "stop" and the polarity of the track circuit current in block B-C is reverse. Conductor section E-C of this block is de-energized, but conductor section B-E of the same block is, of course, energized. Track relay J^b is, consequently, energized in reverse direction, so that signal S^b indicates "caution." The polarity of the track circuit current in block A-B is normal, and both conductor sections for this block are energized. The vehicle V being in block A-B, relay F is energized in normal direction, so that signal S indicates "proceed." As this vehicle enters block B-C, the polarity of the current in its circuit a will be reversed, so that signal S will change to "caution." As the vehicle enters section E-C of this block, current will cease to flow in circuit b, so that relay F will become de-energized, and, consequently, signal S will indicate "stop."

Referring now to Fig. 3, the arrangement of blocks and auxiliary conductor sections is the same as that shown in Fig. 1. The track circuits are likewise the same as those shown in Fig. 1, except that the reactors W are omitted and a single reactance 90 is included between each transformer secondary 3 and one of the track rails. The control of the supply of current to the sections of conductor X is different from that shown in Fig. 1, however, and is as follows:

The rear conductor section for each block is connected in series with the forward section of the block in the rear, and current of normal or reverse polarity is at times supplied to these two sections simultaneously. Considering, for example, section B-E of block B-C and section E-B of block A-B, and assuming that track relays H^a and H^c are energized, the circuit is as follows: from the left-hand terminal of secondary 18 of transformer T^c, through wire 19, front point of contact 20 of relay H^c , wire 21, resistance 22, wire 21^a, conductor

section B-E of block B-C, wire 91, contact 9 of relay H^b , wire 92, conductor section E-B of block A-B, reactor M at the rear end of this conductor section, rails R and R' in multiple, reactor M at the forward end of the latter conductor section, wire 93, reactor M at the rear end of section B-E, rails R and R' of block B-C in multiple, reactor M at the forward end of section E-C, and wire 93 to the middle terminal of secondary 18. The current which flows in this circuit is of normal polarity. When track relay H^c is de-energized, the circuit is from the right-hand terminal of secondary 18 of transformer T^c, through wire 22, back point of contact 20 of relay H^c , and then through the remainder of the circuit as before. The current which then flows in the auxiliary conductor sections is of reverse polarity.

185 The operation of the system shown in Fig. 3 is as follows:

The block immediately in advance of location C being occupied by a vehicle V, track relay H^c is de-energized so that conductor section E-C is de-energized by virtue of the fact that contact 9 of relay H^c is open. The back point of contact 20 of this same relay being closed, current of reverse polarity is supplied to the rear conductor section of block B-C and to the forward conductor section of block A-B. The rear section of block A-B is occupied by a vehicle V, which is equipped with traffic governing apparatus which may be similar to that shown in Fig. 1, or to that shown in Fig. 2. Relay H^b being energized, the auxiliary conductor section under this vehicle V is receiving current of normal polarity so that the signal on such vehicle indicates "proceed." As this vehicle passes point E in block A-B, the current in the circuit b therein becomes reversed, so that the signal on the vehicle changes to "caution" indication. This signal continues to indicate "caution" after the vehicle passes point B, and until it reaches point E in block B-C. After passing this latter point, the vehicle-carried circuit b becomes de-energized, so that the signal on the vehicle changes to "stop" indication.

110 It will be seen that the system shown in Fig. 3 provides for an overlap so far as the vehicle governing apparatus is concerned, that is, that a caution indication is received on the vehicle at some distance in the rear of the block in the rear of an occupied block, and that a stop indication is received on the vehicle at a point some distance in the rear of an occupied block.

120 One important feature of the systems shown herein is that they provide for transmitting two distinctive signals to a vehicle with the use of signaling current of but one frequency. For this reason, the invention

is easily applied to a railway which is already equipped with a signaling system embodying alternating current track circuits, the only substantial changes which are necessary being the installation of the auxiliary conductor X, the reactors M and W, and suitable equipment on the cars or trains. An alternating current transmission line is already in existence in such instances, and this line can be used to supply all the track way current required for the entire vehicle control and signaling system.

Although I have herein shown and described only certain forms of railway traffic controlling systems embodying my invention, it is understood that various changes and modifications may be made therein within the scope of the appended claims without departing from the spirit and scope of my invention.

Having thus described my invention, what I claim is:

1. In combination, a railway track divided into blocks, an auxiliary conductor for each block, means for each block for supplying alternating signaling current to the track rails thereof, means for each block controlled by traffic conditions in advance for supplying alternating signaling current to the auxiliary conductor for the block, a circuit on a vehicle receiving energy from the track rails, another circuit on the vehicle receiving energy from said auxiliary conductors, and vehicle-carried traffic governing means controlled by energy in said circuits.

2. In combination, a railway track divided into blocks, an auxiliary conductor for each block, means for each block for supplying alternating signaling current to the track rails thereof, means for each block controlled by traffic conditions in advance for supplying alternating signaling current to the auxiliary conductor for the block, vehicle-carried means for receiving energy from the track rails and from said auxiliary conductors, and traffic governing means controlled by said vehicle-carried means.

3. In combination, a railway track divided into blocks, an auxiliary conductor for each block, means for each block for supplying alternating signaling current to the track rails thereof, means for each block controlled by traffic conditions in advance for supplying alternating signaling current to the auxiliary conductor for the block, and traffic governing means located on a vehicle and controlled by currents in the track rails and in said auxiliary conductors.

4. In combination, a railway track divided into blocks, an auxiliary conductor for each block, means for each block for supplying alternating signaling current to the track rails thereof and to the auxiliary conductor for the block, means for each block

controlled by traffic conditions in advance for varying the relative polarity of one of said currents, and vehicle-carried traffic governing means controlled by currents in the track rails and in said auxiliary conductors. 70

5. In combination, a railway track, an auxiliary conductor parallel therewith, means for supplying alternating signaling currents to the track rails and to the auxiliary conductor, means controlled by traffic 75 conditions for varying the phase relation of said currents, a railway vehicle, a relay on said vehicle having two windings and a movable member operated in one direction or another according to the phase 80 relation of the currents in said windings, and means on the vehicle for supplying to said relay windings periodically varying currents having the same relative phase relation as the phase relation of currents supplied to the track rails and auxiliary conductor. 85

6. In combination, a railway track divided into blocks, an auxiliary conductor for each block, means for each block for supplying alternating signaling current to the track rails thereof and to the auxiliary conductor for the block, means for each block controlled by traffic conditions in advance for varying the phase relation of said 90 currents, and vehicle-carried means controlled by currents in the track rails and in said auxiliary conductors for giving a proceed or a caution signal according as said currents have one phase relation or another and a stop signal when either current is absent. 95

7. In combination, a railway track divided into blocks, auxiliary conductors for the blocks, means for each block for supplying alternating signaling current to the track rails thereof and to the auxiliary conductor for the block, the supply of one of said currents for each block being controlled by traffic conditions in advance, two 105 vehicle-carried circuits receiving energy from the track rails and auxiliary conductors respectively, traffic governing means on the vehicle, an electron relay interposed between said governing means and one of 110 said circuits, and another electron relay interposed between said governing means and the other of said circuits. 115

8. In combination, a railway track divided into blocks, an auxiliary conductor for each block, means for each block for supplying alternating signaling current to the track rails thereof, a track relay for each block responsive to the signaling current flowing in the rails thereof, means for each block controlled by the track relay of the block next in advance for supplying alternating signaling current to the auxiliary conductor for the block, and traffic 120 governing means located on a vehicle and 125

controlled by currents in the track rails and in said auxiliary conductors.

9. In combination, a railway track divided into blocks, an auxiliary conductor for each block, means for each block for supplying alternating signaling current to the track rails thereof and to the auxiliary conductor for the block, a track relay for each block, the relative polarity of one of said currents for each block being varied by the track relay for the block next in advance, and traffic governing means located on a vehicle and controlled by currents in the track rails and in said auxiliary conductor and responsive to variations in the relative polarity of one of said currents.

10. In combination, a railway track divided into blocks, an auxiliary conductor for each block divided into a forward and a rear section, means for each block for supplying alternating signaling current to the track rails thereof, means for each block for supplying alternating signaling current of one relative polarity or another to the rear section of the corresponding auxiliary conductor according as the block in advance is clear or occupied, and for supplying alternating signaling current to the forward section of the corresponding auxiliary conductor or not according as the block in advance is clear or occupied, and traffic governing means carried on a vehicle and controlled by currents in said track rails and auxiliary conductors and responsive to variations in the phase relation of said currents.

11. In combination, a railway track divided into blocks, an auxiliary conductor for each block divided into a forward and a rear section, means for each block for supplying alternating signaling current to the track rails thereof and to the rear section of the corresponding auxiliary conductor, means for each block controlled by traffic conditions in advance for varying the phase relation of said currents, means for each block for supplying alternating current to the forward section of the corresponding auxiliary conductor or not according as the block in advance is clear or occupied, and train-carried means controlled by currents in the track rails and in said auxiliary conductors and responsive to variations in the phase relation of said currents.

12. Railway traffic controlling apparatus comprising track rails, an auxiliary conductor parallel therewith, means for supplying alternating currents of the same frequency to said rails and conductor, and vehicle-carried traffic governing means controlled by said currents.

13. In combination, a railway track divided into blocks, an auxiliary conductor

divided into a rear and a forward section for each block, means for supplying alternating signaling current to the track rails of each block, means for each two adjacent blocks controlled by traffic conditions in advance for supplying alternating current of one relative polarity or the other to the rear conductor section of the forward block and the forward conductor section of the rear block, means for each block operating when the block is occupied to disconnect the rear conductor section of such block and the forward conductor section of the block in the rear from their source of current supply, and vehicle-carried traffic governing means controlled by currents in the track rails and conductor sections and by the phase relations of such currents.

14. In combination, a railway track, an auxiliary conductor parallel therewith, means for supplying alternating signaling currents of the same frequency but differing in phase to the track rails and to said conductor, a vehicle-carried relay having two windings and responsive to currents displaced in phase therein, vehicle-carried means controlled by said trackway currents for supplying currents to said relay windings of the same frequency and phase relation as the frequency and phase relation of the currents in the track rails and auxiliary conductor respectively, and vehicle-carried traffic governing means controlled by said relay.

15. In combination, a railway track, an auxiliary conductor parallel therewith, a source of alternating signaling current connected across the track rails, a second source of alternating signaling current one terminal of which is connected with one end of said conductor, a reactive winding the middle point of which is connected with the other end of said conductor and the terminals of which are connected with the two track rails respectively, a second reactive winding having its terminals connected with said two rails respectively and its middle point connected with the remaining terminal of said second source, and vehicle-carried traffic governing means controlled by currents in said track rails and auxiliary conductor.

16. In combination, a railway track, an auxiliary conductor parallel therewith, a transformer having a secondary connected across said track rails, a reactance device included in said connection and reactive to current from said secondary but not to current flowing in the same direction from secondary to rails or vice-versa, a second transformer secondary having one terminal connected with one end of said auxiliary conductor, a reactive winding the middle point of which is connected with the other end of said auxiliary conductor, and the

terminals of which are connected with the two track rails respectively, a connection between the other terminal of said secondary and the middle point of the first secondary, and vehicle-carried traffic governing means controlled by currents in said track rails and auxiliary conductor.

17. In combination, a block of railway track, an auxiliary conductor for said block divided into a forward and a rear section, means for supplying alternating signaling current to the track rails of said block, traffic controlled means for supplying alternating signaling current of one relative polarity or the other to the rear section of said conductor, traffic controlled means for supplying alternating signaling current to the forward section of said conductor, and vehicle-carried traffic governing means controlled by the currents in said track rails and said conductor and responsive to the relative polarity of said currents.

18. In combination, a block of railway track, an auxiliary conductor for said block divided into a forward and a rear section, traffic controlled means for supplying alternating signaling current of one relative polarity or the other to the track rails of said block, means for constantly supplying alternating signaling current to the rear section of said conductor, traffic controlled means for supplying alternating signaling current to the forward section of said conductor, and vehicle-carried traffic governing means controlled by the currents in said track rails and said conductor and responsive to the relative polarity of said currents.

19. In combination, a railway track divided into a plurality of successive blocks, an auxiliary conductor for each block divided into a forward and a rear section, means for supplying alternating signaling current to the track rails of each block, traffic controlled means for supplying alternating signaling current of one relative polarity or the other to the rear conductor section of each block and to the forward conductor section of the block immediately in the rear, traffic controlled means for at times discontinuing the supply of signaling current to the forward conductor section of each block, and vehicle-carried traffic governing means controlled by the currents in said track rails and said conductor, and responsive to the relative polarity of said currents.

20. In combination, a stretch of railway track divided into blocks, a track relay for each block having a winding connected across the rails of the block and responsive to reversals of the instantaneous relative polarity of the current in said rails, means for each block including contacts of the track relay for the block next in advance for connecting a source of alternating cur-

rent across the rails of the block of normal or reverse instantaneous relative polarity according as the relay is energized in either direction or is de-energized, and means controlled by each track relay for supplying a second alternating current to the track rails in multiple of the block next in the rear.

21. In combination, a stretch of railway track divided into blocks, a track relay for each block having a winding connected across the rails of the block and responsive to reversals of the instantaneous relative polarity of the current in said rails, means for each block controlled by the relay for the block next in advance for connecting a source of alternating current across the rails of the block of normal or reverse instantaneous relative polarity, and means controlled by each track relay for supplying a second alternating current to the track rails in multiple of the block next in the rear.

22. In combination, a railway track divided into blocks, an auxiliary conductor for each block, means for each block for supplying alternating currents to the track rails and to the auxiliary conductor for the block, means for each block controlled by traffic conditions in advance for reversing the relative polarity of the current in the track rails and vehicle carried traffic governing means controlled by said currents, and the phase relation of said currents.

23. In combination, a stretch of railway track divided into blocks, a track circuit for each block including a source of current and a track relay, means for each block for constantly supplying an alternating vehicle governing current to the rails of the block in multiple from the entrance end of the block to an intermediate point in the block, and means for each block controlled by the track relay for the block next in advance for supplying similar current to the track rails in multiple from said intermediate point to the exit end of the block.

24. In combination, a block of railway track, means for constantly supplying an alternating vehicle governing current to said block from the entrance end to an intermediate point in the block, and means controlled by traffic conditions in advance for at times supplying similar current to said block from such intermediate point to the exit end of the block.

25. In combination, a block of railway track divided into an entrance section and an exit section, means for constantly supplying alternating vehicle governing current to the track rails of said entrance section in multiple, and means controlled by traffic conditions in advance for at times supplying similar current to the rails of said exit section in multiple.

In testimony whereof I affix my signature.
LLOYD V. LEWIS.
